UNITED STATES PATENT OFFICE.

EDWARD WEISSENBORN, OF JERSEY CITY HEIGHTS, NEW JERSEY.

PACKAGE FOR PENCILS.

SPECIFICATION forming part of Letters Patent No. 228,961, dated June 15, 1880.

Application filed April 26, 1880. (Model.)

To all whom it may concern:

Be it known that I, EDWARD WEISSEN-
BORN, of Jersey City Heights, in the county
of Hudson and State of New Jersey, have in-
5 vented a new and useful Improvement in Pack-
ages for Pencils, of which the following is a
specification.

Figure 1 is a view illustrating the method
of forming the packages. Fig. 2 is a plan
10 view of a package containing a bundle of pen-
cils. Fig. 3 is a sectional elevation taken
through the line *x x*, Fig. 2, some of the pen-
cils being removed.

Similar letters of reference indicate corre-
15 sponding parts.

The object of this invention is to furnish
packages for pencils, crayons, and similar ar-
ticles, so constructed as to prevent the pen-
cils or other articles contained in the pack-
20 ages from rubbing against each other, and
which will retain its shape when part or all of
its contents are taken out.

The invention consists in a package for pen-
cils formed of a single strip of paper bent to
25 form two layers or rows of open tubes ar-
ranged back to back; and also in the method
of forming the package by bending a strip of
paper under small rods and over larger rods
30 to form two rows or layers of open tubes,
turning the one layer down upon the other
layer, bringing the open tubes back to back,
withdrawing the small rods, and flattening
down the small loops in a press, as will be here-
after fully described.

35 For convenience I will describe the package
in connection with the method of forming it.

A is a strip of paper of any desired or con-
venient width, one end of which is secured in
a clamp, B, of any convenient construction.
40 From the clamp B the paper is passed down
and a small rod, C, is placed above it. The
paper A is then drawn over a rod, D, of the
exact shape and size of the pencils or other
article for which the package is intended.

45 The paper A is drawn down at the other side
of the rod D, and another small rod, C, is
placed above it, and so on until as many rods
D have been used as it is intended to have
pencils or other articles in a layer, which, in
50 the case of pencils, is usually six. The pa-

per A is then passed under a small rod, C',
placed at a distance from the last small rod
C of the first layer equal to the height of the
package, and is then passed over a large rod,
D, and under a small rod, C, and so on until 55
as many rods D have been used as it is de-
signed to have pencils or other articles in the
second layer. The last end of the paper A is
then held tight, the first end is released from
the clamp B, and the block or frame E that 60
holds the rods C D of the first layer is turned
over upon the block or frame F that holds the
rods C D of the second layer, and the two
ends of the paper are overlapped, as shown in
Fig. 3. 65

The paper A should be dampened before
being applied to the rods C D, to cause it to
retain its shape after the said rods C D have
been removed.

Glue, paste, or other cement may be ap- 70
plied to the convex sides of the paper A above
the rods D, and to the parts of its ends that
are to be overlapped, so that the paper, when
the rods C D are removed, will retain its
place. The rods C are withdrawn and the pa- 75
per A and rods D are placed in a press and
put under pressure, which flattens down the
loops of the paper formed around the rods C
to a level with the uncovered sides of the rods
D, as shown in Fig. 3. The rods D can now 80
be removed and replaced with the pencils G
or other articles for which the package is in-
tended.

If desired, pencils G may be used instead
of the metal rods D; but I prefer to use the 85
metal rods D, as it avoids any danger of in-
juring or crushing the pencils in the press.

With this construction a package of two
layers or rows of open grooves arranged back
to back is formed, which will retain its shape 90
when some or all the pencils are removed,
and into which the pencils can be readily in-
serted.

Having thus described my invention, I claim
as new and desire to secure by Letters Pat- 95
ent—

1. A package for pencils, constructed of a
single strip of paper, A, and having two lay-
ers or rows of open tubes arranged back to
back, as set forth. 100

2. The method of forming the package, substantially as herein shown and described, which consists in bending a strip of paper under small rods and over larger rods to form 5 two rows or layers of open tubes, turning the one layer down upon the other layer, bringing the open tubes back to back, withdraw-

ing the small rods, and flattening down the small loops in a press, as set forth.

EDWARD WEISSENBORN.
